UNITED STATES PATENT OFFICE.

THOMAS L. BARKER AND JOSEPH C. HORNBAKER, OF WESTFIELD, INDIANA.

WASHING-MACHINE.

SPECIFICATION forming part of Letters Patent No. 393,092, dated November 20, 1888.

Application filed February 11, 1888. Serial No. 263,705. (No model.)

To all whom it may concern:

Be it known that we, THOMAS L. BARKER and JOSEPH C. HORNBAKER, of Westfield, in the county of Hamilton and State of Indiana, have 5 invented a new and Improved Clothes-Roller, Washing-Machine, and Wringer, of which the following is a full, clear, and exact description.

The object of our invention is to provide a new and improved machine combining a 10 clothes roller and wringer with a washing-machine, and which is simple and durable in construction, very effective in operation, and saves considerable time and labor.

The invention consists in the construction 15 and arrangement of certain parts and details and combinations of the same, as will be fully described hereinafter, and then pointed out in the claims.

Reference is to be had to the accompanying 20 drawings, forming a part of this specification, in which similar letters of reference indicate corresponding parts in all the figures.

Figure 1 is a side elevation of our improvement in the position for adjusting the clothes. 25 Fig. 2 is a plan view of the same. Fig. 3 is a longitudinal sectional elevation of the same in the position for washing, and Fig. 4 is a vertical cross-section of the same on the line $x-x$ of Fig. 3.

Our improved machine is provided with the 30 water-box A, provided with a metallic bottom, B, and having in its middle a crosswise-extending partition, C, which divides said box A into two compartments, D and D'. On the 35 under side of the box A is held a furnace, F, provided with the usual grate-bars, E, on which opens a door, E², for the admission of fuel. Below the grate-bars E² is the ash-pit E³, and from the rear end of the furnace E a chimney, 40 E⁴, extends upward.

On top of the compartments D and D' can be fitted the roller-box F, adapted to turn on the upper ends of curved arms G, pivoted at G' to the top edge of the partition C. A spring-45 arm, H, is secured to the outside of the box A and extends upward, being provided near its upper end with a catch, H', adapted to engage one end of an arm G, so as to hold the latter in position, as shown in Fig. 1. The box 50 F is of the same size as the compartments D

and D', and is open at the bottom and provided with a metallic top, F', having in its middle an aperture, F², for letting the water run out when said box F is turned upside down for wringing.

The lower edges of the box F are grooved at 55 F³, and fit in corresponding grooves, A', formed on the top edges of the ends and sides of the box A, so as to make a tight connection between the respective compartment, D or D', 60 and the said box F. In the latter is held a hollow clothes-cylinder, I, provided in its rim with a number of apertures, I', for the escape of water and steam from the interior of the cylinder I. The latter is secured to a shaft, I², 65 mounted to rotate in suitable bearings formed in the sides of the box F, and part of said shaft is hollow and provided inside of the cylinder I with perforations, while the other part is solid and is provided on the outer end with a 70 crank-arm, I³, for turning said shaft I² and the cylinder I.

The outer end of the hollow part of the shaft I² can be connected with a coupling, J, of any 75 approved construction, and opening into a pipe, J', extending downward into the furnace E, in which it is coiled several times, and then passes out of the furnace and downward and upward to form the bend J², which opens into the compartment D. Thus when the machine 80 is in operation and the compartment D is filled with water, the latter can pass into the bend J² and from the same into the pipe J', in which it is heated in the furnace E and converted into steam, which enters the hollow 85 shaft I² through the coupling J, and passes through the perforations of said shaft I² into the interior of the clothes-cylinder I.

Across the rim of the cylinder I, extend a 90 number of bars, K, pivoted at K' to one end of the cylinder I, and secured by set-screws K² or other means to the other end of said cylinder I. The clothes to be washed and otherwise treated are passed under the bars K, which are then secured in place by the said 95 set-screws K², so that the clothes are firmly held in place on the rim of the cylinder I.

On each side of the cylinder I is held a presser-roller, L or L', respectively, each mounted to rotate in spring-bars N, secured by 100

one end to the inside of the box F, and having their other ends fastened to an arm, O, centrally secured to one end of a shaft or pin, O', held in the side of the box F and extending to the outside of the same. On the outer end of the shaft or pin O' is secured a lever-arm, O², provided with an inwardly-extending pin, O'', engaging one of a series of apertures, O', formed in the respective side of the box F, and serving to adjust the position of the arm O, thereby increasing or diminishing the tension of the spring-bars N, so as to throw the presser-rollers L toward or from the clothes-cylinder I.

15 In either of the compartments D or D' can be suspended a pan, P, provided with flanges P', adapted to engage the grooves A' in the upper edges of the sides and ends of the box A. Said pan P is used in rinsing the clothes, 20 as hereinafter more fully described.

The operation is as follows: The compartments D and D' are filled with a suitable quantity of water and then a fire is started in the furnace E, so that said water in the compartments D and D' is heated. The box F is held upside down, as shown in Figs. 1 and 2, so as to enable the operator to adjust the clothes to be washed on the cylinder I in the manner above described. The levers O² are then adjusted so as to throw the presser-rollers L in contact with the clothes. The operator now disengages the arm H from the arm G and turns the box so that the part F' is on top, and the lower grooved edges engage the grooves A', formed on the upper edges of the sides and ends of the compartment D, as illustrated in Figs. 3 and 4. As soon as the box F is in position, then the operator couples the coupling J on the outer hollow end of the shaft I², so 40 that the steam generated in the pipe J' can pass into the hollow cylinder I, and through the apertures I' into the clothes held on the outside of the rim of said cylinder I. The operator then turns the crank-arm I³, whereby 45 the cylinder I is rotated, and the clothes held on said cylinder are constantly passed through the heated water contained in the compartment D. Thus it will be seen that the steam operates from the inside of the cylinder 50 against the clothes and the hot-water in the compartment D soaks through the clothes, which again pass alternately through the presser-rollers L, which press part of the water and steam out of the same. The impurities contained in the clothes are carried with the water and steam pressed out of the clothes by the rollers L and L'. The turning of the shaft I is continued until the clothes are washed clean. The pan P is then suspended 55 in the compartment D and filled with clean water, after which the coupling J is disconnected from the hollow end of the shaft I² and the box F is swung over the compartment D', and then the operator again turns the crank-arm I³, whereby the clothes are passed through the clean water in the pan P and are thereby rinsed. After this operation is completed the

box F is again swung upward in the position shown in Fig. 1, and the arm H is again connected with the arm G, so as to hold the latter and the box F in position. The clothes are then removed from the cylinder I by unscrewing the set-screws K² and throwing the bars K upward. In order to wring the clothes, the box F is placed over the compartment D 75 in an upside-down position, so that the top F' is the bottom, and its opening F² discharges into said compartment D. The cylinder I is turned and the clothes are passed between the rollers L and L' and the cylinder I, whereby 80 all the water is pressed out of the clothes and the latter are delivered into a basket or other suitable receptacle.

Having thus fully described our invention, we claim as new and desire to secure by Letters Patent—

1. In a washing-machine, the combination, with a water-box, of a reversible roller-box pivotally connected to said water-box, substantially as described.

2. In a washing-machine, the combination, with a water-box, of arms pivoted to the said box, and a roller-box having an open bottom and apertured top and pivoted at about its center between the said arms, substantially as 95 described, whereby provision is made for swinging the roller-box above the water-box and reversing the same, as set forth.

3. In a washing-machine, the combination, with a water-box, of curved arms pivoted to the box, a roller-box having an open bottom and apertured top and pivoted between the said arms, and an arm secured to the water-box and having its free end adapted to engage the curved arms, substantially as herein shown 105 and described.

4. In a washing-machine, the combination, with a water-box divided into two compartments, of curved arms pivoted to the box at about the center thereof, a roller-box having an open bottom and pivoted at about its center between the said arms, and a clothes-carrying and pressure rollers journaled in the said box, substantially as herein shown and described.

5. In a washing-machine, the combination, with a water-box, of a reversible roller-box having an open bottom and apertured top and pivotally connected to said water-box, a clothes-cylinder journaled in the said box, spring-arms secured to the sides of the box, and pressure-rollers journaled in the said springs, substantially as herein shown and described.

6. In a washing-machine, the combination, with a box having apertures in its sides, of springs having one end secured to the box, rollers journaled in said springs, a shaft projecting through the box, an arm to which the other end of the springs are secured attached to said shaft, and a lever-arm on the said shaft and having an inwardly-extending end, substantially as herein shown and described.

7. In a washing-machine, the combination, with a water-box provided with a partition

forming two compartments in the said box, of an arm fulcrumed on the top of the said partition, a roller-box pivoted on the said arm and adapted to be moved over either of the said compartments, a clothes-cylinder held to rotate in the said box and carrying the clothes, adjustable presser-rollers held on the rim of the said cylinder, and a rinsing-pan held in

one of the compartments of the said box, substantially as shown and described.
